PROJECTION SURFACE PARTICULARLY FOR USE IN CONNECTION WITH
ADVERTISEMENTS

Application filed August 1, 1928, Serial No. 296,854, and in Austria August 12, 1927.

This invention relates to projection surfaces of very large dimensions which are erected in the open and adapted for the projection of advertisements and the like. Such 5 large surfaces are directly exposed to the wind-pressure and must be provided with structures, screens or screening surfaces for obstructing undesired light.

According to the present invention, the 10 essential feature of the projection surface resides in the fact that the small individual freely swinging and reflecting plates which form the projection surface are each combined with a screen or a screening surface, 15 which participates in the swinging movement of the small plate.

One mode of carrying out the present invention is illustrated by way of example on the accompanying sheet of drawings in 20 which:—

Fig. 1 shows a projection surface of very large size and the projection apparatus arranged on a road.

Figs. 2 and 3 are detail views in perspective and diagrammatic side elevation respectively.

A frame 1 of iron, reinforced concrete or the like is arranged across a road and takes up the entire width of the same, the said 30 frame being at such a height from the level of the road, that it does not obstruct the traffic. A network consisting of horizontal and vertical wires 2 and 3 (Figs. 2 and 3) is stretched across the frame 1. Small plates 35 4 of white enameled sheet-iron, aluminium plates or of any other suitable material are suspended freely movable from the vertical wires 3 within the meshes thus formed. At the bottom and lateral sides of the small 40 plates is provided a small clearance, so that they can give way to the wind-pressure and swing to both sides. The freely suspended plates form a closed surface, because the intermediate spaces or clearances are not visible from some distance. The plates are 45 provided with small lugs by which they are suspended if bent round the wire.

According to a further construction of the invention the small plates are bent at an angle and by means of their bending edge

or corner are mounted on the wire, so that a part of the same projects horizontally and each plate has its shade in order to keep away the strange light from the projection surface in known manner.

The projection apparatus can be arranged, 5 in towers 6, which also may be used as advertising pillars.

Owing to the dividing of the surface into 10 individual swinging plates the wind is deprived of the greatest part of the attacking surface, so that the frame 1 or the entire supporting structure can be of a considerably 15 weaker construction than it is possible in the case of solid surfaces. The vertical intermediate spaces between the plates are not enlarged 20 during the swinging motion, this taking place only in the event of the horizontal intermediate spaces, and therefore in case of a stronger wind-pressure only a horizontal lining will be visible on the projected image, the said lining becoming finer if the 25 height of the plates is reduced. Therefore the distance between the vertical wires can be of such a large size, as will be allowed by the 30 rigidity of the construction. Thus according to the present invention the width of the 35 plates exceeds the height of the same.

We claim:—

1. A projection surface including a plurality of individual freely swingable reflecting plates forming the projection surface, and a screening surface combined with each plate and swingable therewith.

2. An arrangement as claimed in claim 1, 35 characterized in that each of said plates is bent to provide the screening surface, the latter being normally disposed in a substantially horizontal position.

In testimony whereof we have affixed our 40 signatures.

REMIGIUS GEYLING.
PAUL PLANER.
